UNITED STATES PATENT OFFICE

106,204

DESIGN FOR AN AMUSEMENT MACHINE CABINET

Harry E. Knupp, Detroit, Mich., assignor to A. C.
Novelty Company, Detroit, Mich., a corporation of Michigan

Application February 25, 1937, Serial No. 67,845

Term of patent 7 years

To all whom it may concern:

Be it known that I, Harry E. Knupp, a citizen of the United States, residing in Detroit, in the county of Wayne and State of Michigan, have invented a new, original, and ornamental Design for Amusement Machine Cabinets, of which the following is a specification. Reference may be had to the accompanying drawing, forming a part of this specification, wherein the figure is a perspective view of an amusement machine cabinet

embodying my design.

I claim:

The ornamental design for an amusement machine cabinet, as shown.

HARRY E. KNUPP.
